(57) **CLAIM**

The ornamental design for a building, as shown and described.

DESCRIPTION

FIG. 1 is a right front perspective view of a building, showing my new design;

FIG. 2 is a left front perspective view, thereof;

FIG. 3 is an elevational view of one side, thereof;

FIG. 4 is an elevational view of the other side, thereof;

FIG. 5 is a front elevational view, thereof;

FIG. 6 is a top plan view, thereof;

FIG. 7 is a side elevational view as in FIG. 3, but showing the two tilt-up window covers in a raised position; and,

FIG. 8 is a right front perspective view of the article shown in FIG. 7.

The broken line representation of the attached building shown in FIGS. 1 and 2, is included solely for illustrative purposes, forming no part of the claimed design.
